INSULATED CONNECTER FOR OUTLET BOXES

Filed Jan. 26, 1929

Inventor:
Homer G. Knoderer,
by Charles E. Tullar
His Attorney.

UNITED STATES PATENT OFFICE

HOMER G. KNODERER, OF FAIRFIELD, CONNECTICUT, ASSIGNOR TO GENERAL ELECTRIC COMPANY, A CORPORATION OF NEW YORK

INSULATED CONNECTER FOR OUTLET BOXES

Application filed January 26, 1929. Serial No. 335,357.

My invention relates to an improved combination of elements of utility in connection with armored conductors, such as are employed in house wiring and the like and more particularly to an improved insulating bushing and connector combination for securing armored conductors to outlet boxes and the like.

An object of my invention is to provide an arrangement of parts which will insure that the insulated wires of armored conductors are protected from the sharp end edges of the armor without the necessity for particular thought or care on the part of the workman in making the installation.

A further object of my invention is to provide a combination of insulating bushing and connector which will also protect the conductors from any sharp edges on the part of the connector, which extends into the outlet box, so that the conductor insulation will not be injured thereby.

A further object of my invention is to provide a construction which will permit connectors and insulating bushings to be readily assembled and enable the combined connector and bushing to be shipped and sold as a unit and handled by the workman as a unit when making an installation.

A further object of my invention is to provide an arrangement which when the installation is completed will enable an inspector readily to determine whether or not the installation has been properly made.

A further object of my invention is to provide a simple and rugged arrangement of parts which makes it impossible for the bushing to be removed from the connector after the armor stripped ends of the conductors are inserted into the bushing and which permits the workman to force the armored conductor into position for clamping without danger of forcing out the bushing, and which will insure that the conductors are protected from the sharp end edges of the armor when the armor has been pushed into the connector far enough to permit it to be secured therein by the clamping means thereof.

While my invention is particularly useful in connection with armored conductors, it is

also advantageous for use in connection with flexible metallic conduit which is secured by connectors in a similar way to outlet boxes and the like and into which conduit the conductors are drawn and the electrical connections made after the conduit system has been installed. In such an arrangement my invention protects the conductors from injury by the sharp edges on the conduit and connector and also provides a smooth uninterrupted runway for the drawn in wires. 55

My invention will be better understood when considered in connection with the following specification and accompanying drawings and its scope will be pointed out in the appended claims. 60

Referring to the drawings, Fig. 1 is a side elevation, with part broken away, of an armored conductor with the right-hand end stripped of armor; Fig. 2 is an axial section of the connector with my insulating bushing in place; Fig. 3 are sections of a junction box wall and connector retaining nut; Fig. 4 is a perspective view of the outer end of the connector; Fig. 5 is an assembled view of the 70 several parts shown in Figs. 1, 2 and 3; Fig. 6 is a side elevation of another form of armored conductor showing the sharp end edge customarily formed in the cutting of the armor to bare or strip the ends of the insulated 75 wires; Fig. 7 is a part side elevation and part section of a flexible metallic conduit assembled in a connector provided with my insulating bushing; Fig. 8 is a perspective view with part broken away of the inner end of a 80 different form of connector and insulating bushing; Fig. 9 is a similar view of another form of connector and insulating bushing; Fig. 10 is a view of the application of my invention with a different form of clamping 85 means and Fig. 11 represents a modified construction of insulating bushing. 90

As is well known, the armor of armored conductors and the flexible metallic conduits of commerce are composed of continuous 95 metal strips or ribbons profiled in cross section and coiled helically so that the edges thereof become interlocked with a certain amount of freedom to slip upon each other when the finished article is bent. It is customary in 100

installing armored conductors and flexible metallic conduit to cut the profiled metallic strip by suitable means such as a hack saw. This usually leaves a sharp projecting end 5 edge or corner which is apt to penetrate the insulation of the conductors. Also, unless special care is taken by the wireman, the hack saw may cut into or through the insulation of the wires of armored conductors directly beneath the sharp end edge thereby increasing the liability of an electrical contact 10 between the armor and the wires. After a portion of the armor has thus been severed and removed, the armored conductor is secured by suitable means such as a connector to the outlet box into which the wires project. The manipulation of these wires by the wireman in making connections is likely further to injure the insulation on the wires by reason 15 of sharp edges or projections on the armor or the connector.

In accordance with my invention I provide an improved insulating bushing which projects between the wires and the armor of the 20 armored conductor to form an insulating and protecting sleeve to protect the wires from injury by sharp edges or projections on the armor and which bushes the end of the connector which extends into the outlet box 25 to protect the wires against injury from the connector. Referring to Figs. 2 and 5 it will be seen that the bushing 4 is mounted in the connector 8. As will be more particularly set forth hereafter, the bushing is constructed 30 so that when it has been inserted into the connector it will be securely retained in the connector and the bushing and connector may be handled as a unit. After a portion of the armor of the armored conductor has been removed 35 the projecting wires are inserted through the connector and bushing as above described. In Fig. 1 the projecting wires of the armored conductor are shown at 2 and the armor at 3. In order to enable the bushing 40 to be readily inserted between the wires and the armor, I prefer to use an armored conductor which is provided with a wrapping 1 which may be of paper. After the armor has been cut and a portion removed so as to leave 45 the projecting wires a portion of the paper wrapping 1 may be pulled out and the wrapping severed for a distance back into the armor sufficient to accommodate the sleeve of the bushing which projects between the wires 50 and the armor. While I at present prefer to use armored conductors with such a wrapping my invention is also applicable to other forms 55 of armored conductors where there is a small amount of looseness or space between the conductors 2 and the armor 3 which permits the bushing to be forced into place.

I prefer to make the insulating bushing 4 in the form of a split tube of fiber or other suitable resilient insulating material provided at the inner or outlet box end with

two spaced shoulders, one of which is an end flange 5 and the other a bead 6 between which shoulders the inturned flange or contracted part 7 of the connector 8 is located when the bushing is in place in the connector. When 70 the bushing is forced into the shouldered or contracted part 7 of the connector 8 the bead 6 snaps through the contracted part 7 and the latter is then embraced on opposite sides by the spaced shoulders of 75 parts 5 and 6 and serves thereby to hold the insulating bushing definitely positioned therein with an annular clearance space 9 between the main bore 10 of the connector 8 and the outside of the main tubular portion of the bushing. This clearance space 80 is open at its outer end and closed at its inner, as shown in Fig. 2.

In order to facilitate the entrance of the split insulating bushing 4 into the space between the insulated conductors 2 and the inner surface of the armor 3, the outer corners 15 thereof adjacent the split are preferably rounded off, as shown in Fig. 2, and the outer end of the bushing is preferably made slightly beveled or tapering.

I preferably construct the bushing so that when it is snapped into place in the connector the longitudinal edges adjacent the split of the bushing come into abutting relation with 95 each other. This serves to resist the collapse of the bushing and provides a complete insulating sleeve. It is within the scope of my invention, however, to make the slit in the bushing sufficiently wide so that when it 100 is contracted to insert it in the connector the edges come into abutting relation and when the bushing comes into place its resiliency causes it to be held firmly in place. The flange 5 and the bead 6 on the bushing contribute to the resilient action of the bushing.

When the conductors 2 have been inserted through the bushing the collapse of the bushing is prevented so that the workman may grasp the connector 8 in his hand and apply 110 force to drive the sleeve into place between the armor and the wires and to drive the connector 8 over the armor 3 without danger of pushing the bushing out of the connector.

The particular form of connector 8 shown 115 in section in Figs. 2 and 5 is shown in perspective in Fig. 4. I provide such a length of bushing 4 with respect to the connector 8 that when the armor 3 has been forced into the connector far enough to enable the armored conductor to be fastened into the connector by tightening the screw 12 the sleeve of the bushing will have been forced between the wires and the armor to the necessary distance to 120 protect the wires from the sharp edges of the armor. In other words when the armored conductor has been inserted into the connector far enough to enable it to be secured by the clamping means it necessarily follows that the bushing is properly located. After 125 130

the connector has been clamped to the armor the threaded end of the connector 8 is entered through the hole in the outlet box wall 13, or other wall through which the wires are to be led, and the connector is secured to the wall by the nut 14 as indicated in Fig. 5.

It will be observed that the flange 5 of the bushing 4 projects over and protects the wires from injury from the edges of the connector 7. It will also be observed that the flange 5 of the bushing is in a position where it may be readily seen by looking into the outlet box. If, therefore, an inspector observes that the armor is properly clamped in the connector 15 and observes the flange 5 of the bushing, he knows at once that the insulating bushing is in place and that the job has been properly done. This is a feature of considerable importance since if the bushing were inside of the contracted portion 7 of the connector it 20 would be practically impossible for the inspector to determine whether or not the bushing was present without disassembling the connection. Even should the inspector disassemble a few connections in a building and 25 find that the bushings were in place he would even then not be sure that the bushings were in place in the other connections unless he disassembled all of them. With my arrangement no disassembling at all is necessary and with 30 the inspection can be made quickly and with certainty. Moreover since the bushing may be shipped in place in the connector and handled as a unit by the wireman the wireman 35 does not need to exercise the thought and care which would be necessary if separate bushings were used which he would have to remember to insert between the wires and the armor before securing the armor in the connector. It 40 will be observed that the sleeve of the bushing projects within the connector and is protected by the connector so that it will not be damaged by the handling and boxing and shipment of the assembled units comprising 45 the connectors and bushings.

Fig. 6 represents another form of armored conductor which omits the wrapping 1 of the armored conductor shown in Fig. 1. This figure also indicates at 11 the sharp 50 corner which customarily results when the armor is cut with a hack saw as heretofore described.

While my invention is of particular utility in connection with armored conductors, it 55 may also be advantageously used with flexible metallic conduits into which the wires are drawn after the conduit installation has been made. Fig. 7 shows such an application of my invention.

It will be apparent to those skilled in the 60 art that my invention is not limited to any one particular type of connector. Fig. 8 illustrates another type of well known connector with my bushing inserted therein. Fig. 9 illustrates still another type of well-

known connector. Fig. 10 illustrates a modified arrangement for clamping armored conductors in an outlet box. In this case the member 16 is mounted inside the outlet box and when the screw passing through the hole 17 is forced down the member 16 is tilted and clamps the armor 3 in the box. With this type of clamp my bushing 4 may also be used and shipped with the clamping member 70 as a unit. It will thus be seen that my improved arrangement is applicable to many different kinds and types of connectors.

While I at present prefer to use a bushing which is split throughout its length it is apparent that it is within the scope of my invention to use a bushing which is split or cut through a portion only of its length, as indicated in Fig. 11, the split portion being at the end upon which the shoulders 5 and 6 are provided. Such a bushing may be either 85 inserted into the connector from the end opposite the restricted portion or may be inserted from the restricted end of the bushing if the bushing is suitably tapered, as indicated in Fig. 11, so that the uncut portion will 90 pass through the restricted portion of the connector.

What I claim as new and desire to secure by Letters Patent of the United States, is:

1. The combination with an armored electrical conductor and an outlet box, of a connector provided with means for securing it to the armored conductor and to the outlet box and an insulating bushing comprising a split cylindrical sleeve located between the armor 100 and conductors and provided with means for attaching it to said connector the parts being constructed and proportioned so that when the securing means is operative to connect the armored conductor to the connector the bushing will be located properly to protect and insulate the conductors from the armor and connector.

2. The combination with an insulator shield comprising a split tubular body, one end portion of which is fashioned to form spaced, outwardly and radially projecting members between which is an annular recess, of a tubular metallic body, one end portion of which is provided with an inwardly extending flange 110 adapted to seat in the recess of said shield 115 to retain the tube against displacement from the shield.

3. The combination with a tubular body having an inwardly and radially directed wall, of a shield of insulating material arranged in the bore of said body, and means on said shield adapted to be arranged at opposite sides of said wall for retaining said shield against displacement from said body.

4. In combination with an insulated electric conductor and a sheathing therefor, said conductor having an end portion projecting outwardly from an end of said sheathing, of a coupling adapted to connect said conductor

- and its sheathing to an electrical fixture, said coupling comprising, a tubular body adapted to be passed over the end of said sheathing and having a substantially longitudinally extending shield member therewith adapted to project into said sheathing in surrounding and protecting relation with said insulated conductor.
5. The combination with a connector having a conductor passageway, of a split cylindrical insulating bushing having means thereon for retaining the same against accidental displacement from within the passageway of the said connector so as to constitute a unit part thereof, the walls of the split portion at one end of said bushing being cut along a plane at an angle to the longitudinal axis of said bushing.
6. In combination with an insulated electric conductor and a sheath therefor, said conductor having an end portion projecting outwardly from an end of said sheathing, of a coupling adapted to connect said conductor and its sheathing to an electrical fixture, said coupling comprising a tubular body adapted to be passed over the end of said sheathing and having a substantially longitudinally extending cylindrical split shield member adapted to project into said sheathing in surrounding and protecting relation with said insulated conductor, and an attaching flange formed on said shield member and attached to said tubular body.
7. In combination with an insulated electric conductor and a sheathing therefor, said conductor having an end portion projecting outwardly from an end of said sheathing, of a coupling adapted to connect said conductor and its sheathing to an electrical fixture, said coupling comprising, a tubular body adapted to be passed over the end of said sheathing and having a substantially longitudinally extending cylindrical shield member therewithin spaced relation from the inner walls of said tubular body, said shield member being adapted to project under said sheathing and in surrounding, protecting and supporting relation with said insulated conductor.
8. In combination with an insulated electric conductor and a sheathing therefor, said conductor having an end portion projecting outwardly from an end of said sheathing, of a coupling adapted to connect said conductor and its sheathing to an electrical fixture, said coupling comprising, a tubular body adapted to be passed over the end of said sheathing and having a shield member therewithin comprising a substantially cylindrical body portion adapted to surround said insulated conductor and to project under the end portion of said sheathing to protect said insulated conductor from the abrasive action of said end portion, said shield member having an outwardly extending annular flange fixedly attached to said tubular body, and clamping
- means provided on said body and adapted to grip said sheathing to retain said coupling thereon.
9. A coupling for armored cables comprising, a tubular body having a sheathing receiving aperture for receiving the end portion of an armored cable and a substantially cylindrical split shield member having a body portion extending longitudinally within said aperture and concentric therewith for insertion under the cable sheathing, and an attaching flange formed on said body portion and attached to said tubular body.
10. In combination with an armored cable comprising an insulated electric conductor and a sheathing therefor, a coupling comprising, a tubular body having a sheathing receiving aperture for receiving the end portion of said armored cable and a substantially cylindrical split shield member having a body portion extending longitudinally within said aperture and concentric therewith, and an attaching flange formed on said body portion and attached to said tubular body, said body portion having a tapered end to facilitate the insertion of said body portion under the cable sheathing.
11. In combination with an armored cable of a coupling comprising, a tubular body having a sheathing receiving aperture for receiving the end portion of said armored cable and a substantially cylindrical split shield member having a body portion extending longitudinally within said aperture and concentric therewith, and an attaching flange formed on said tubular body, said body portion having a tapered end to facilitate the insertion of said body portion under the cable sheathing.
- In witness whereof, I have hereunto set my hand this 23rd day of January, 1929.
- HOMER G. KNODERER.
